UNITED STATES PATENT OFFICE.

CLARKE HAYES, OF FRANKLIN, PENNSYLVANIA, ASSIGNOR OF ONE-HALF
TO BRYAN H. OSBORNE, OF SAME PLACE.

CASING-HEAD FOR OIL-WELLS.

SPECIFICATION forming part of Letters Patent No. 661,913, dated November 13, 1900.

Application filed August 6, 1900. Serial No. 26,063. (No model.)

To all whom it may concern:

Be it known that I, CLARKE HAYES, a citizen of the United States, residing at Franklin, in the county of Venango and State of Pennsylvania, (whose post-office address is Franklin, Venango county, Pennsylvania,) have invented certain new and useful Improvements in Casing-Heads for Oil-Wells; and I do hereby declare the following to be a full, clear, and exact description of the invention, such as will enable others skilled in the art to which it appertains to make and use the same.

My invention relates to improvements in casing-heads for oil-wells; and it consists in an improved form of casing-head hereinafter described and claimed.

Heretofore it has been the practice in operating oil-wells to throw away the belled-over upper section of the casing used in drilling the well and to supply in place thereof a separate section of tubing screw-threaded for the connection of the casing-head, which latter has been ordinarily attached to the casing by a screw-thread joint. This practice has been objectionable for many reasons. Notable among these is the fact that the belled-over upper section of the casing, or, in other words, the "drillers' casing-nipple" so called, must be entirely thrown away after having once been used, for the reason that the wells vary in depth, and it rarely occurs that a casing-nipple used with one well may be used for another well. In addition to this is the extra labor and expense in cutting and fitting the short section, to which is immediately connected the casing-head as commonly used. My invention is intended to overcome these objections, and I do this by the provision of the casing-head, which may be utilized in connection with the ordinary drillers' casing-nipple, the latter being allowed to remain and be utilized.

My invention will be understood by reference to the accompanying drawings, wherein the same parts are indicated by the same letters used on the several views.

Figure 1 represents a vertical sectional view of my improved casing-head in position as used in the mouth of the ordinary drillers' casing-nipple. Fig. 2 represents a side elevation of my improved casing-head, and Fig.

3 is a sectional view of the modified form of casing-head.

A represents the ordinary drillers' casing-nipple, having belled-over upper edge A⁰. 55 This drillers' casing-nipple is commonly used and well known, and its object and manner of forming the same need not be specifically described herein.

B represents the casing-head, constructed according to my invention. This casing-head comprises the body portion B⁰, having lateral extensions B, screw-threaded, as at b', for the connection of pipes and tubing. The casing-head has also a flaring upper end B², provided with an annular seat b² for the ring or collar C, which rests loosely upon the said seat and is provided with a central opening c for the passage of the tubing D, which tubing passes axially through the casing-head B in the usual manner. This tube D is fitted with a thimble or collar D', which constitutes a support for said tube, and this thimble or collar rests upon a heavy annular ring D⁰, which in turn rests upon the ring C, which is provided with a seat c⁰ for the said ring D⁰, as seen in Fig. 1. The ring D⁰ is preferably provided with a pair of links d⁰, by means of which ropes or chains may be attached to said rings for hoisting the tube D from the well when desired or for lowering the same into the well. The arrangement of the thimble or collar D' as a support for the tube D is intended as a safeguard to prevent the tubing falling into the well should the said tubing D be broken off above the casing-head by any accident—such, for instance, as the blowing over of the derrick commonly used in connection with an oil-well, but not shown in the drawings.

The body B⁰ of the casing-head B may be 90 in my invention substantially of the same shape as in casing-heads commonly in use now. The main feature of my invention and that which constitutes the chief improvement consists of the reduced tubular extension B³ 95 at the bottom end of the casing-head. This tubular extension B³ may be cast solid with the casing-head, as shown in Fig. 1, or it may be a separate casting B⁴, as shown in Fig. 3. This tubular extension B³ is formed of such a diameter as to fit snugly within the upper end of the drillers' casing-nipple A, the an-

nular enlargement or shoulder B^5 on the casing-head resting upon the belled-over edge A^0 of the casing-nipple, as shown in Fig. 1, and thus supporting the casing-head. Although 5 the extension B^3 should fit snugly within the nipple A , it is preferable to use a small amount of packing E of a suitable fibrous material, such as tow, to form a perfectly close joint.

Where the tubular extension (indicated by 10 B^4 in Fig. 3) is formed separately from the casing-head B , as shown in Fig. 3, the latter is provided with screw-threads b^5 , and the upper end of the tubular extension B^4 is provided with male screw-threads b^4 , which engage the female screw-threads b^5 in the casing-head above referred to.

Whether the casing-head and the tubular extension to fit within the casing-nipple are cast integral or whether they are cast separately and united by a screw-thread joint, as above described, the construction and the appearance, as well as the use of the casing-head, remain substantially the same.

In using my improved form of casing-head 25 the drillers' casing-nipple is allowed to remain undisturbed, and it merely becomes necessary in fitting the well for pumping to seat the extension on the casing-head into the nip-

ple and afterward connect the tubing in the ordinary well-known manner.

The main advantage of my improved casing-head arising from the convenience is the saving of time and trouble, and the great saving of expense will be too well appreciated and understood by any one familiar with the operation of oil-wells to need further emphasis herein.

Having thus described my invention, what I claim, and desire to secure by Letters Patent of the United States, is—

In an oil-well apparatus, the combination with the drillers' casing-nipple having its belled-over upper end; of a casing-head having a tubular extension thereon fitting within the belled-over end of the drillers' casing-nipple and having an exterior concave curved shoulder resting upon said belled-over end of the drillers' casing-nipple, substantially as described.

In testimony whereof I affix my signature 50 in presence of two witnesses.

CLARKE HAYES.
